PIANO-LAMP.

1,353,033.

Specification of Letters Patent. Patented Sept. 14, 1920.

Application filed January 23, 1917. Serial No. 144,009.

To all whom it may concern:

Be it known that I, CLEBURNE EBERHART, Jr., a citizen of the United States, residing at Buffalo, in the county of Erie and State 5 of New York, have invented new and useful Improvements in Piano-Lamps, of which the following is a specification.

This invention relates to a lamp which is more particularly designed for use in 10 illuminating the key board of an upright piano and the music and reading matter which may be supported on the rack of the front wall of the piano immediately above the key board. It is the object of this invention to produce a simple, compact and inexpensive lamp for this purpose which will efficiently illuminate the space in front 15 of the piano and which is so constructed that the same can be readily and easily attached to and removed from the front walls 20 of pianos and not project above the lid thereof and which is neat and artistic so as not to detract from the appearance of the piano.

25 In the accompanying drawings: Figure 1 is a fragmentary vertical section of an upright piano equipped with one form of lamp embodying my invention. Fig. 2 is a bottom plan view thereof, on an enlarged scale. 30 Fig. 3 is a detached perspective view of the same looking at it from the rear. Figs. 4 and 5 are fragmentary vertical longitudinal sections, on an enlarged scale, taken on the correspondingly numbered lines in Fig. 2. 35 Fig. 6 is a fragmentary sectional view showing a modification of my invention.

Similar characters of reference indicate corresponding parts throughout the several views.

40 Although my improved piano lamp is applicable to upright pianos which may vary as to the details of construction that, for example, which is shown in the drawings comprises a case having an upright front 45 wall or board 1, a vertically swinging lid 2 which projects forwardly over the upper edge of the front wall and provided on the underside of its front part with a bead or molding 3 which is adapted to project down- 50 wardly past the upper end of the front wall, and a music rack 4 arranged on the front wall, and playing keys 5 mounted on the casing below the front wall, these features

being similar to those found in upright pianos as commonly constructed.

55 My improved piano lamp which is adapted to be mounted on the front wall of a piano of this character is preferably constructed as follows:

60 6 represents the body or wall of the hood or deflector which is preferably constructed of sheet metal bent into substantially semi-cylindrical form in cross section so as to leave a light outlet passage throughout the length thereof on its underside. At its opposite ends the body of the casing is provided with two heads 7, 8 which are preferably circular and constructed of sheet metal to give the hood or deflector an ornamental appearance. This hood is adapted to be 65 supported in a horizontal position lengthwise above the key board and music rack and in front of the piano casing, so that the rays of light from the illuminating means arranged within the hood will be 70 directed downwardly upon the key board and music or the like and brilliantly illuminate the same. The lighting element or medium preferably consists of an elongated or tubular electric light bulb 9 which is 75 arranged lengthwise within the central part of the hood, as shown in Figs. 1 and 2. Various means may be provided for removably 80 mounting the electric light bulb within the hood so that this bulb may be renewed from 85 time to time as the same burns out. The preferred means for this purpose, however, consists in employing such an electric lamp fitting in which the base 10 of the lamp is mounted in a tubular metallic shell 11 having its rear end removably seated in a metallic cap 12 which latter serves as the head 90 8 at one end of the lamp hood or deflector. By this means the shell 11 and the head 8 of the hood may be of standard construction such as now generally used by the electric trade and permits of producing a detachable mounting for the electric lamp bulb on the hood without involving an undue outlay in cost of manufacture. The head 100 8 of the hood may be connected with the respective end of the hood in any suitable manner, for instance by holding the same by means of solder in the bore of said body so that the cord 13 containing the electric 105 conducting wires for the lamp bulb ex-

tends through an insulating sleeve 14 of rubber, fiber, vulcanite or similar material which is secured in a central opening in the head 8 by means of a set screw 15 or 5 other suitable means. By this means the lamp upon burning out may be readily renewed by first sliding the shell 11 and cap 12 lengthwise from the body of the hood together with the lamp base and bulb 10 mounted thereon and after the bulb has been renewed the shell may in like manner be again slipped lengthwise back into the body so that the bulb is retained in its proper position within the hood. The lamp 15 base within the shell may also be provided with the usual standard switch for turning the current on and off from the lamp bulb which switch may be operated by a pull chain 16 extending downwardly through a 20 tubular guide 17 arranged on the underside of the lamp shell.

For the purpose of retaining in shape that end of the hood body which contains the lamp socket and associated parts a stiffening 25 ring 18 is provided which is secured within the bore of the hood body around the lamp shell by welding or otherwise which ring bridges the longitudinal opening in the underside of the hood body and prevents the 30 lower edges thereof from spreading out of place. The lower part of this stiffening ring is provided in its outer edge with a notch 19 which is adapted to receive the pull chain guide 17 of the lamp fitting, thereby serving 35 as a means for bringing the pull chain in the proper position relative to the hood and retaining these parts against rotation relatively to each other. In order to yieldingly hold the lamp bulb in place within the hood a 40 detent device is provided which preferably consists of a detent or retaining spring finger 20 arranged on the lower part of the stiffening ring and adapted to yieldingly engage with the outer side of the shell behind an external annular bead 21 thereon, as shown in 45 Fig. 5. By exerting sufficient outward pull on the bulb fitting to overcome the frictional grip of the spring finger 20 it is possible to easily and conveniently withdraw the lamp 50 bulb and associated parts from the hood for inspection, adjustment or renewal. To prevent upward displacement of the lamp bulb under the pressure of the spring finger 20 an abutment or filling 22 is provided within the 55 body diametrically opposite the finger which abutment is preferably, though not necessarily, made of metal integrally with the stiffening ring in the form of a strip projecting inwardly from this ring, as shown in Fig. 5. 60 In order to avoid heating the hood unduly a ventilating opening 23 is provided for permitting the hot air within the hood which is generated by the heat of the electric bulb to escape from the upper part of 65 the hood. This ventilating opening is pref-

erably arranged in the upper part of the end head 7, as shown in Figs. 3 and 4, and permits the hot air within the hood to escape slowly to the exterior thereof, thereby preventing the hood from becoming unduly 70 heated as would otherwise be liable to occur if this hot air were confined within the hood.

In the absence of any provision to prevent it, rays of light from the illuminating medium within the hood would be able to escape 75 upwardly through the ventilating opening which would not only be objectionable in appearance but also injurious to the eyes of persons who might be grouped around the piano. To prevent this a baffle or shield 24 80 is provided which projects downwardly from the upper part of the hood so as to be arranged between the illuminating element and the ventilating opening and thereby obstruct the passage of any rays of light from 85 the lamp bulb through this ventilating opening to the exterior of the hood. In its preferred form this baffle is formed from the metal at the upper edge of the head 7 by cutting out a portion of this metal and bending 90 the same downwardly, as shown in Fig. 4.

Any suitable means may be employed for mounting this hood on the upper edge of the 95 front wall of the piano casing but the construction shown in Figs. 1-5 of the drawings is preferred and as there shown the same is constructed as follows:

25, 25 represent two supporting brackets mounted on the body of the hood adjacent to opposite ends thereof and adapted to detachably engage with the upper edge of the front wall of the piano casing. Each of these brackets is preferably constructed mainly of sheet metal and comprises a horizontal arm 26 projecting rearwardly from the rear side of the body of the casing adjacent to its lower rear edge, a relatively stiff front jaw 27 projecting upwardly from the rear end of the arm 26, a horizontal web 28 projecting rearwardly from the upper end of the front jaw and a rear upright jaw 29 projecting downwardly from the rear end of this web. The front end of each arm 26 may be connected with the rear part of the 115 hood body in various ways, for instance, by means of a flange 30 projecting upwardly from the front end of this arm and secured to the rear side of the hood body by electric welding, soldering, or any other suitable 120 manner. The front and rear jaws and the web of each bracket together form a hook the mouth of which opens downwardly whereby this bracket may be engaged with its mouth over the upper edge of a piano 125 front wall so that the front and rear jaws are arranged respectively in front and in rear of the front piano wall and the web is arranged above the upper edge of this wall, as shown in Fig. 1. In order to permit this 130

hook-shaped bracket to engage with the upper edges of the piano front walls which may vary in thickness to some extent the rear jaw of the bracket is provided with a yielding bearing which preferably comprises a horizontal spring tongue or flexible rear jaw 31 projecting toward the other bracket, said spring tongue being attached to the respective rear jaw either by rivets 32, as shown in Figs. 1 and 3, or in any other approved manner. Upon placing a bracket of this construction with its mouth over the upper edge of the piano front wall so that its web engages with the top of this wall, the front jaw engages with the front side thereof and the spring tongue with the rear side thereof, as shown in Fig. 1, so that the lamp will be reliably held against displacement on the piano front wall. The upper end of the spring tongue of each bracket is preferably arranged so close to the front jaw so that the same will grip the rear sides of piano front walls which vary in thickness and thereby securely hold the lamp in its proper place. The presence of the horizontal web of each bracket across the upper end of the piano front wall will not interfere with the closing of the lid 2 of the piano casing over the brackets inasmuch as the metal from which these brackets are made is comparatively thin and does not have the effect of raising the lid to an abnormal extent when the latter is lowered upon the brackets. Owing to the front jaw of each bracket extending downwardly from the front end of its companion web along the front side of the front wall it is possible for the lid to be lowered into its closed position notwithstanding the presence of the bead on the underside of the same inasmuch as this bead simply overlaps the front jaw of each bracket, sufficient space being usually present between this bead and the adjacent surface of the front wall to permit these parts to clear each other.

In order to avoid marring or injuring the finished surfaces of the piano front wall and the lid the inner and outer surfaces of the front jaw and horizontal web of each bracket are preferably covered with a protecting or cushioning material 33 which may consist of felt or the like, as shown in Figs. 1 and 3.

By arranging the spring tongues of the attaching brackets horizontally the same may be raised out of the way of the music rack and permit the same and any parts mounted thereon to be folded back into the front wall of the casing without interference.

When, however, the music rack is fixed on the front casing wall or the parts are so organized that interference with the brackets and their spring retaining tongues is impossible then each rear jaw 290 of each

bracket may be made somewhat longer and its spring tongue 310 may project upwardly from the lower end of this jaw into engagement with the inner side of the piano front wall 100, as shown in Fig. 6.

70

For the purpose of reducing to a minimum the transfer of heat from the hood body to those parts of the brackets which are supported on the piano front, an opening 34 is formed in the arm of each bracket, thereby reducing the amount of material at these points and the amount of heat which the same can carry accordingly and thereby preventing scorching any polished surfaces of the front part of the piano.

80

When this lamp is mounted on the front of a piano with the lid down, as shown in Fig. 1, the supporting means for the hood are practically concealed from view so as not to detract from the appearance of the piano while at the same time furnishing efficient illumination of the music and the key board.

85

Furthermore, the construction of this piano lamp is very compact and the same can be so mounted on the piano that it does not encroach upon any of the space within the case or on top of the lid which may be required for articles of decoration or other purposes. Moreover, the construction of this lamp is very simple and it is possible to produce the same at comparatively low cost.

90

I claim as my invention:

1. A piano lamp comprising a hood having a longitudinal light passage in its underside and a stiffening member which bridges said passage and connects the walls on opposite sides of the same and provided with an outwardly opening notch, and an electric lamp bulb fitting slidably into said hood and provided with a laterally projecting chain guide engaging with said notch.

100

2. A piano lamp having a bracket which includes an upright relatively stiff front jaw adapted to engage with the outer side of a piano front, a horizontal upper arm adapted to engage with the upper edge of the piano front and projecting rearwardly from the upper end of said front jaw, a flexible rear jaw connected with the rear end of the upper arm and arranged below the latter and adapted to engage with the inner side of the piano front, said flexible jaw including a leaf spring which has its sides arranged vertically and which is arranged with its length horizontally and transversely relatively to said upper horizontal arm, and said front jaw adapted to carry the piano lamp.

110

3. A piano lamp having a bracket which includes an upright relatively stiff front jaw adapted to engage with the outer side of a piano front, an upper horizontal arm adapted to engage with the upper edge of the piano front and projecting rearwardly from the upper end of said front jaw, a flexible

120

22
rear jaw arranged at the rear end of said upper arm and below the top of the latter and adapted to engage with the inner side of the piano front, and a lower horizontal arm projecting forwardly from the lower end of said front jaw and adapted to carry the piano lamp at its front end, said flexible

jaw being constructed of a leaf spring which has its sides arranged vertically and which is arranged with its length horizontally and ¹⁰ transversely relatively to said upper horizontal arm.

CLEBURNE EBERHART, JR.
